UNITED STATES PATENT OFFICE.

ARTHUR ADELBERT NEWELL, OF MELLETTE, SOUTH DAKOTA.

ROPE-CLAMP.

SPECIFICATION forming part of Letters Patent No. 734,469, dated July 21, 1903.

Application filed January 3, 1903. Serial No. 137,864. (No model.)

To all whom it may concern:

Be it known that I, ARTHUR ADELBERT NEWELL, a citizen of the United States, and a resident of Mellette, in the county of Spink 5 and State of South Dakota, have invented a new and Improved Rope-Clamp, of which the following is a full, clear, and exact description.

The object of this invention is to provide 10 novel details of construction for a rope-clamp which adapt said clamp for the support of material which may be connected by the clamp to a rope whereon the clamp is mounted and also to enable the convenient change 15 in position of the clamp on the rope and a hooked connection of the clamp with a ring on a chain or an equivalent fixture on a rope that is to be joined to the rope whereon the clamp is mounted and which may be used in 20 various other connections, as will hereinafter appear.

The invention consists in the novel construction and combination of parts, as is hereinafter described, and defined in the 25 appended claims.

Reference is to be had to the accompanying drawings, forming a part of this specification, in which similar characters of reference indicate corresponding parts in all the figures. 30 Figure 1 is a perspective view showing the application of the improvement. Fig. 2 is a partly-sectional side view of the rope-clamp and hook adjusted to clamp a rope. Fig. 3 is a like view, with the exception that parts 35 are adjusted to release a rope, the latter being indicated by dotted lines. Fig. 4 is an enlarged perspective view of a latch-dog that is a novel detail of the invention, and Fig. 5 is a side view of the clamp seen in direction 40 of the arrow *x* in Fig. 2.

The body of the rope-clamp is preferably cast into form from metal, and consists of an essentially tubular shell 6, convexed near one end on its exterior and having an essentially corresponding concavity *a* on the same 45 wall opposite the convex surface.

An elongated opening *b* is formed in the shell 6 diametrically opposite the concavity *a*, the edges of the shell that define said opening being preferably sloped downwardly and

toward the opposite side wall, these converged edges *b'* and wall merging into the upper extremity of a hook 7, that is curved downwardly and outward therefrom.

Immediately above the concavity *a* the wall 55 of the shell 6 is apertured to lighten it, and at the transverse lower edge of said aperture two opposite inwardly-projecting sharpened spurs *c* are formed, as is clearly indicated by full and dotted lines in Fig. 5. On the concave wall of the shell 6, near the hook 7, three spaced spurs *d* are projected inwardly, said spurs being suitably spaced apart, as shown in Fig. 5.

From the upper termination of the sloped 65 edges *b'* the wall of the shell is converged somewhat, so as to diametrically reduce the open end, which receives the rope end *A* when the device is to be mounted thereon.

At or near the upper ends of the side edges 70 *b'*, that define the width and length of the opening *b* in the shell 6, a latch-dog 8 is held to rock, as is clearly shown in Figs. 2, 3, and 5. The dog 8 comprises an essentially L-shaped block of metal, which may be shaped 75 as shown in Fig. 4, having its two angularly-diverged members *8^a* *8^b* braced at their junction by the web-wall *8^c*.

A transverse perforation *e* is formed in the latch-dog 8 at the junction of the members 80 *8^a* and *8^b*, and two opposite perforations are formed in the wall of the shell 6 to receive a pivot *e'*, which when secured therein after insertion through the perforation *e* will dispose the members *8^a* *8^b* projected inwardly and 85 free to receive rocking adjustment.

A preferably V-shaped notch *g* is formed in the free end of the member *8^a*, and a like notch *h* is produced in the free end of the member *8^b* of the latch-dog 8. Preferably the 90 member *8^a* is of somewhat greater length than the member *8^b*, and the longer member of the latch-dog may be rocked, so as to project it out of the shell 6 or be disposed within the same, as shown in the drawings.

In the application of the device to a line or 95 rope for service the latch-dog 8 is adjusted as shown in Fig. 3, which will afford a clear passage through the shell 6 for the insertion of the rope *A* therethrough. When the shell 100

6 is positioned on the rope A at a desired point, the latch-dog 8 is rocked, so as to press the member 8^a against the rope A and force the latter into contact with the side of the shell that is opposite the dog.

The partial rotation of the longer limb or member 8^a in the direction of the arrow α' in Fig. 3 by pressure on it, whereby to introduce the shorter member 8^b within the shell 6, as described, serves to rock the longer limb 8^a into contact with the rope A, as shown in Fig. 2.

From the relative positions had by the members 8^a 8^b of the latch-dog when it is adjusted as shown in Figs. 1 and 2 the rope A will be pressed toward the concavity α in the shell 6 and be forced into engagement with the spurs c d therein, which will prevent the shell 6 from slipping on the rope, and it will be seen that if the rope is held at a point above the shell and draft force is applied to the hook 7 the limb 8^a will be rocked into closer engagement with the rope and clamp the shell 6 tighter upon the rope.

From the foregoing it will be manifest that the angularly-bent latch-dog 8 effects the automatic locking of the shell 6 and hook 7 upon the rope A by merely pressing the dog member 8^a as a lever from the position shown in Fig. 3 to that indicated in Fig. 2.

When it is desired to release the clamp from the rope, the shell 6 is grasped and the rope also below the shell and held while the shell is pressed upward. This will rock the dog 8 slightly on its pivot and correspondingly move the dog member 8^a outward from the shell, so that it may be taken hold of and rocked more fully outward or into the position shown in Fig. 3, which will release the clamp from the rope.

The improvement may also be utilized for a rope-clamp with any desired attachment thereto—such, for example, as with a ring,

a snap-hook, a swivel-snap, or a swivel, as may be desired.

Having thus described my invention, I claim as new and desire to secure by Letters Patent—

1. A rope-clamp, comprising a shell having an elongated opening at one side extending through the lower end thereof, a rearwardly-turned hook at the lower end of said shell forming the termination thereof, the shell having a concavity on its rear side opposite the lower end of the elongated opening, spurs in the concavity, and an L-shaped dog pivoted to rock at the upper end of the elongated opening with its short arm normally extending transversely of the central opening of the shell to engage the rope therein and its longer arm extending downwardly in said elongated opening at the side of the shell, to a point opposite said spurs, and adapted to swing into engagement with the rope to clamp the same into engagement with the spurs, the free ends of the L-shaped dog being each provided with a large notch adapted to embrace a portion of the circumference of the rope to more firmly engage the same.

2. A rope-clamp, comprising an elongated shell having an opening in one side extended to one end thereof, and also having a concavity near said end opposite the opening, spurs in the concavity near each end thereof, an integral hook on the shell below the concavity, and a substantially L-shaped dog pivoted at its angle in the shell at its opening, said dog having its members notched at their free ends to engage a rope.

In testimony whereof I have signed my name to this specification in the presence of two subscribing witnesses.

ARTHUR ADELBERT NEWELL.
